UNITED STATES PATENT OFFICE

WILLIAM B. WHITSITT, OF BALTIMORE, MARYLAND

APPARATUS FOR CLEANING RAILROAD CARS

Application filed August 19, 1927. Serial No. 214,182.

In order to preserve the exterior finish of railroad cars, and have the cars present a neat appearance to the traveling public, it is necessary to clean these cars at frequent 5 intervals.

In many instances a comparatively thick film of gum covers the exterior of a car, and it is very difficult, as well as expensive, to clean a car in this condition as it requires 10 four men working two days to clean a badly gummed car which is expensive, not only from the standpoint of the salaries of the men, but also from the loss of the use of the car.

15 The object of my invention is to provide an apparatus whereby railroad cars can be more thoroughly cleaned, and at less expense than has heretofore been possible. In actual use by the employment of my apparatus, heavily gummed cars have been cleaned 20 in fourteen minutes with two operators and a car more thoroughly cleaned than has heretofore been possible.

25 In the drawings:
Figure 1 is an end elevation of a car cleaning machine embodying my invention.

Figure 2 is a side elevation of my improved machine.

Figure 3 is a top plan view of Figure 2.
30 Figure 4 is a sectional view on the line 4—4, Figure 2, looking in the direction of the arrow.

Figure 5 is a rear elevation of the brush rack.

35 Figure 6 is a side elevation of the brush rack with the brushes mounted thereon.

Figure 7 is an end elevation of my improved car washing machine adapted for a stationary mounting on the fixed base.

40 In the drawings I have illustrated in Figure 1 a car cleaning machine designed to be propelled longitudinally along the sides of the car to be scrubbed, the car being stationary. This machine is intended to be used 45 primarily in terminals where the number of cars to be cleaned is small. In Figure 7 I have illustrated a machine of the same general construction as the self propelling machine in Figure 1, but it is permanently placed on foundations, one on each side of

the car to be scrubbed, and a car to be scrubbed is pulled by any suitable means through the scrubber and washing machine.

The reference numeral 14 designates a base of any suitable construction mounted upon 55 the wheels 15 which I designed to run upon tracks 16 of suitable gage laid parallel to the tracks of a railroad system. This base is provided with a tank 17 in which a suitable cleaning or scrubbing fluid is stored. A 60 frame 18 is suitably mounted on the base 14 and is slideable transversely of said base by means of the screw 19 operated by a crank wheel 20, either manually or by power. This frame 18 has stirrups 21 in which are journaled suitable rollers which run on the track 22.

In moving the machine relative to the car, the power is obtained from the motor 35, through gears 36, 37, 37' and 38 on shaft 38, 70 thence by belt or chain 38², belt 38³, to shaft 38⁴ and to gear 32'. If the clutch is in gear with gear 33, then the power is through shaft 32², thence to pinion 23, gear 24, pinion 25, gear 26, shaft 26', belt or chain 28, shaft 29 75 to belt or chain 30.

Referring more particularly now to Figure 4 it will be seen that if the clutch 31 is engaged with one of the bevel gears 32, 33, the machine will travel in one direction, and if 80 the clutch is engaged with the other bevel gear the machine will travel in the other direction. The clutch is made to engage with whatever gear is desired by operating the hand crank wheel 34.

85 35 is a motor of suitable construction mounted in the frame 18 on the shaft of which is a pinion 36 which drives the gear wheels 37 and 38 through pinion 37'. A crank 39 is operated by the motor 35 through 90 the chain of gears, and connected to this crank is a pitman 40 which is pivotally connected at this upper end to a walking beam 41 mounted in a suitable bearing 42. 43 is a counterbalance weight adjustably secured on 95 the outer end of the walking beam 41 outside of the frame 18, as clearly shown in Figure 1. The brush rack is illustrated in detail in Figures 5 and 6 and comprises parallel spaced plates 44 which are suitably con- 100

- nected by braces 45. The rack is provided with shackles 46 which are adapted to receive the guide rods 47 which are secured to the frame 18 whereby the rack is free to reciprocate on the guide rods 47. A pitman 48 is pivotally connected to the inner end of the walking beam 41 while its other end is pivotally connected to the bearing 49 secured on the rear face of the brush rack, as clearly shown in Figures 1 and 6 whereby when the pitman 41 is operated the rack, through the pitman 48 is reciprocated and the rack is guided in its reciprocation by means of the guide rods 47.
- 15 The plates 44 of the rack are provided with aligned openings or perforations 50 in which rods 51 are slidably mounted, the rods being provided with a nut 52. Secured to the outer end of these rods 51 is a brush 53. 54 is a 20 coil spring around the rods 51, one end of said spring being seated on the plate 56', while its other end is seated on the brush head whereby normally the brushes are maintained in the positions shown in Figure 6.
- 25 These brushes are thus resiliently mounted in order that they may adapt themselves to any irregularity presented on the surface with which they come in contact thereby insuring an intimate contact with and a thorough cleaning of the surface of the car.

The tank 17 is connected by suitable piping to a pump 55 operated by belt 56 from the motor 35. A pipe 57 leads from the discharge end of the pump to a nozzle, or opening, 58 35 which is supported at the top of the frame 18 on a bracket 59 in such position (see Figure 1) that the fluid from the pump will be delivered to the brushes on the side of the car.

40 The pressure of the brushes 53 against the sides of the car can be varied by operating the hand crank wheel 20. By turning this wheel the screw 19 causes the frame 18 to be moved in and out in relation to the side of the car and the base structure 14, and this relation of the brushes to the car can be varied when the machine is in operation.

The solution used in scrubbing the cars is pumped from the tank 17 through the rotary pump 55 to the spray 58 and thence to the brushes and side of the car, the surface fluid or solution dripping from the side face of the car and the brushes to the trough 60, from whence it flows through a suitable pipe to the tank 17 and may be used over again.

In the stationary machine illustrated in Figure 7 the surplus solution dripping from the brushes and the side of the car flows into the trough 60 from whence it flows to the stationary tank placed adjacent to the foundation of the machine.

The general details of the stationary machine shown in Figure 7 are the same as those described in connection with the self-

propelling machine and, therefore, need no specific description.

The motor 35 is used for operating the entire machine, the one motor serving power for giving vertical reciprocating motion, operating the rotary pump 55 and driving the propelling gears to propel the machine along the tracks 16.

As the car passes through my improved cleaning machine the gum, grease, etc., is thoroughly cleaned from the car by the application of the solution and the scrubbing action of the brushes 53 against the side of the car. After this is accomplished that part of the car thus cleaned may be suitably washed to remove all traces of the acid or cleaning agent used in connection with the scrubbing brushes, after which the car is then pulled away ready for service.

I am aware that changes may be made in the details of construction herein shown without departing from the spirit of my invention and the scope of the appended claims.

What I claim is:

1. In a car cleaning machine, a base, a frame movably mounted on said base, means to move said frame toward and from the surface to be cleaned, a device mounted on said frame to supply fluid to the surface to be cleaned, a walking beam mounted on said frame, means to operate said beam, a reciprocating rack operatively connected to said beam, and brushes on said rack.

2. In a car cleaning machine, a base, a frame carried by the base, means to move said frame transversely of the base to regulate the projection of the frame toward the car to be cleaned, vertically disposed guides on one side of the said frame, a brush rack including parallel spaced bars having sets of aligned perforations, rods slidably mounted in said perforations, a brush mounted on each set of said rods, a coiled spring on each rod one end of which is seated on the brush rack while the other is seated on the head of the brush, shackles secured to said brush rack and slidably mounted on the said vertically disposed guides, means to deliver liquid to said brushes, and a trough positioned below the said brushes to catch the overflow of liquid from said brushes, and means to reciprocate said rack with its brushes.

3. In a car cleaning machine, a frame, means on said frame for supplying a fluid to the surface to be cleaned, a walking beam mounted on said frame, means to operate said beam, a reciprocating rack operatively connected to said beam, and brushes on said rack.

4. In a car cleaning machine, a frame, means on said frame to supply fluid to the surface to be cleaned, a walking beam mounted on said frame, means to operate said beam, a reciprocating rack operatively connected

- to said beam, brushes on said rack, and means connected to said beam for counterbalancing the weight of the rack and the brushes. 12. In a car cleaning machine, a frame, vertically disposed guides on said frame, a rack mounted to reciprocate vertically on the guides, brushes carried by the rack, a walking beam mounted on the frame and operatively connected to the rack, means for actuating said beam for reciprocating the rack and the brushes carried thereby, and means connected to the beam for counterbalancing the weight of the rack and the brushes. 70
5. In a car cleaning machine, a frame, vertically disposed guides on said frame, a rack mounted to reciprocate vertically on the guides, brushes carried by the rack, a walking beam mounted on the frame, a pitman rod connecting said beam with the rack, 10 means for actuating said beam for reciprocating the rack and the brushes carried thereby, and means connected with the beam for counterbalancing the weight of the rack and the brushes. 75
15. 6. In a car cleaning machine, a frame, a rack reciprocably mounted on the frame, a plurality of superimposed brushes comprising brush bars provided with brush bristles carried by the rack and extending transversely thereof, and means for reciprocating the rack. 80
20. 7. In a car cleaning machine, a frame, a rack reciprocably mounted on the frame, a plurality of superimposed brushes comprising brush bars provided with brush bristles carried by the rack and extending transversely thereof, means for reciprocating the rack, and coacting means for counterbalancing the weight of the rack and brush bars. 85
25. 8. In a car cleaning machine, a frame, a rack reciprocably mounted on the frame, a plurality of superimposed brushes comprising brush bars provided with brush bristles carried by the rack and extending transversely thereof, a walking beam for reciprocating the rack, means for vibrating said beam, and means connected to the beam for counterbalancing the weight of the rack and brush bars. 90
30. 9. In a car cleaning machine, a frame, a rack reciprocably mounted on the frame, a plurality of superimposed brushes mounted on the rack and extending transversely thereof, a fluid supply device arranged to discharge fluid down upon said brushes, and a collecting trough arranged below the brushes to collect the drain water and conduct the same to a desired point. 95
35. 10. In a car cleaning machine, a frame, a rack reciprocably mounted on the frame, a plurality of superimposed brushes mounted on the rack and extending transversely thereof, a fluid receptacle, a fluid supply device arranged to discharge fluid down upon said brushes, and a collecting trough arranged below the brushes to collect the drain water and conduct the same to said receptacle. 100
40. 11. In a car cleaning machine, a frame, vertically disposed guides on said frame, a rack mounted to reciprocate vertically on the guides, brushes carried by the rack, a walking beam mounted on the frame and operatively connected to the rack, and means for actuating said beam for reciprocating the rack and the brushes carried thereby. 105
45. 12. In a car cleaning machine, a frame, vertically disposed guides on said frame, a rack mounted to reciprocate vertically on the guides, brushes carried by the rack, a walking beam mounted on the frame and operatively connected to the rack, means for actuating said beam for reciprocating the rack and the brushes carried thereby, and means connected to the beam for counterbalancing the weight of the rack and the brushes. 110
50. 13. In a car cleaning machine, a base, a frame movably mounted on the base, means to move said frame toward and from the surface to be cleaned, a device mounted on said frame to supply fluid to the surface to be cleaned, a walking beam mounted on said frame, means to operate said beam, a reciprocating rack operatively connected to said beam, brushes mounted on said rack, and means connected to the beam for counterbalancing the rack and the brushes. 115
55. 14. In a car cleaning machine, a brush rack including parallel spaced bars having each a plurality of pairs of aligned perforations, a pair of rods slidably mounted in each pair of perforations in each bar, a brush mounted at each end on a pair of the rods, and a coiled spring on each rod, one end of which bears on the rack while the other end bears against the brush. 120
60. In testimony whereof I affix my signature.
WILLIAM B. WHITSITT. 125
